US00D705730S

(12) **United States Design Patent**
Kretzschmar et al.

(10) **Patent No.:** **US D705,730 S**
(45) **Date of Patent:** **** May 27, 2014**

(54) **MULTI-RECEPTACLE ELECTRICAL CORD END**

(75) Inventors: **Edwin N. Kretzschmar**, Leander, TX (US); **Attila Bendeguz**, Austin, TX (US); **James B. A. Tracey**, Austin, TX (US)

(73) Assignee: **Great Stuff, Inc.**, Austin, TX (US)

(**) Term: **14 Years**

(21) Appl. No.: **29/416,283**

(22) Filed: **Mar. 20, 2012**

(51) LOC (10) Cl. **13-03**

(52) U.S. Cl.

USPC **D13/133; D13/110**

(57) **CLAIM**

The ornamental design for a multi-receptacle electrical cord end, as shown and described.

DESCRIPTION

FIG. 1 is a perspective view of a multi-receptacle electrical cord end showing our new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken line portion in the figure drawing views is included for the purpose of illustrating unclaimed environment and forms no part of the claimed design.

1 Claim, 4 Drawing Sheets
